UNITED STATES PATENT OFFICE.

BERNHARD ADOLF OTTO PROLLIUS, OF COPENHAGEN, DENMARK.

CENTRIFUGAL LIQUID-SEPARATOR.

SPECIFICATION forming part of Letters Patent No. 767,956, dated August 16, 1904.

Application filed October 26, 1903. Serial No. 178,623. (No model.)

To all whom it may concern:

Be it known that I, BERNHARD ADOLF OTTO PROLLIUS, of 50 Torvegade, Copenhagen, Denmark, have invented certain new and useful 5 Improvements in Centrifugal Apparatus, of which the following is a specification.

This invention relates to improvements in centrifugal machines, and has for its principal object to provide a lining by means of 10 which the liquid may be effectively separated without swirling or churning of the milk or other liquid being operated upon.

With this and other objects in view, as will hereinafter more fully appear, the invention 15 consists in the novel construction and arrangement of parts hereinafter described, illustrated in the accompanying drawings, and particularly pointed out in the appended claims, it being understood that various 20 changes in the form, proportions, size, and minor details of the structure may be made without departing from the spirit or sacrificing any of the advantages of the invention.

In the accompanying drawings, Figure 1 is 25 a sectional elevation of a centrifugal machine provided with a lining constructed in accordance with the invention. Fig. 2 is a sectional plan view of the same. Fig. 3 is an elevation of the lining removed from the machine. 30 Fig. 4 is a view corresponding to Fig. 1, illustrating the centrifugal machine provided with a plurality of concentrically-arranged linings. Fig. 5 is a sectional plan view of the device shown in Fig. 4.

Similar letters of reference are employed 35 to indicate corresponding parts throughout the several figures of the drawings.

The bowl or drum α of the centrifugal machine may be of any approved construction, 40 in the present instance being shown as comprising a main cylinder or body portion having threaded upper and lower ends for the attachment of correspondingly-threaded cap and bottom pieces and at the top is a discharge-tube l for the milk and an outlet p for the cream.

In an annular space in the bottom section 45 of the drum or bowl is placed the flanged disk c , provided with an annular row of perforations d , and to the central portion of this disk

is secured the lower end of an inlet-tube b , the upper end of which is secured to the top of the cap-piece and serves for the introduction of the whole milk or other fluid to be separated.

From the periphery of the tube extends a series of radially-disposed blades e , which serve to carry the milk around with the drum or bowl and prevent the swirling action which occurs where a smooth bowl is employed, and 60 all of these blades are connected at their upper ends to a ring f and at their lower ends are secured to the disk c .

Extending around the series of blades is a lining g that in the present instance is formed 65 of comparatively thin sheet metal and is convoluted to present in plan an approximately star-shaped contour, the outer points of which rest against the inner wall of the drum or bowl, as shown more clearly in Fig. 2. The 70 convolutions are arranged in helical form, presenting a series of channels which are arranged at but a slight angle from the vertical, and hence form a plurality of ascending planes, up which the fluid may travel, and in 75 its transit opportunity is afforded for the separation of the particles of different specific gravity. At the top of the lining is a conical collar h , which leads inward over the ring f , and at the base portions of the convolutions the metal is extended outward in order to assist in directing the skimmed milk toward the periphery of the bowl at 80 the top of the lining. The collar h fits immediately within the conical portion of a ring 85 i and is carried by the cap or cover k of the bowl, this ring having a cylindrical portion which forms at the top of the bowl an annular milk-space in communication with the milk-outlet tube l , while the extreme outer edge 90 of the collar i is arranged at a short distance from the inner wall of the bowl in order to form a comparatively narrow annular passage for the skim-milk. The lining is provided with two sets of openings, the openings 95 m being placed at the root of the corrugations and affording passages for the inward flow of the cream which may be separated from the milk during its transit through the 100 passages afforded by the corrugations,

cream, owing to its lighter specific gravity, flowing inward toward the cream zone, while the milk is held outward and rises gradually along the inward wall of the bowl to finally 5 escape through the outlet *l*.

At the crown portions of the corrugations or at one side thereof are openings *n*, which are arranged on that side of the convolutions opposite the direction of travel of the bowl 10 and lining, so that the milk can pass outward through these openings without churning and will be distributed in the milk zone near the outer portion of the bowl.

In the operation of the device the whole 15 milk is introduced through the tube *b* and travels outward through the openings *d* in the disk *c*, and it immediately commences to separate, being traveled gradually upward against the inner wall of the lining, and 20 thence passes outward from a zone of relatively small circumferential velocity to a zone of much greater circumferential velocity, where, especially at the outer portions of the convolutions, it will flow outward through the 25 openings *n* to the outside of the lining. In the various channels between the inner wall of the bowl and the lining the partly-separated liquid will be acted upon in such manner that the cream, being of lighter specific gravity, 30 will move inward through the openings *m*, while the skim-milk, on account of the formerly-mentioned smaller velocity, will gather along the outer front sides of all of the screw-threads or helical convolutions, and by the 35 movement of the latter it will be lifted or propelled upward and toward the outlet pipe or pipes *l*.

The cream-outlet, consisting of a screw with an eccentric hole, can be advanced to or re- 40 moved from the center by turning the screw.

In Figs. 4 and 5 is shown a lining comprising a plurality of concentric members of substantially the same construction as that previously described. These members are first

inserted in place by screwing them down one 45 over the other, the necessary spacing distance between the several members being provided for by soldering or otherwise securing them to the lower disk *c* and by providing each with a separate conical ring for securement to the 50 inlet-tube *b*. In this modification the central tube is reduced in length and extends only to the upper portion of the innermost lining member; but as all of the members are secured to this tube the whole may be taken out after 55 first removing the tube by merely grasping the tube *b*. The operation is substantially the same as that previously described, with the exception that it is in most cases more effective by reason of the fact that the whole-milk volume is divided into a series of thin concentric layers.

Having thus described the invention, what is claimed is—

1. In a centrifugal machine, a lining convoluted in transverse section, and provided with perforations near the base and crown of each of the convolutions. 65
2. In a centrifugal machine, a lining formed of a metallic cylinder provided with convolutions arranged on helical lines and forming rapidly-ascending planes, there being perforations at the base and crown of each of such convolutions. 70
3. The combination with a centrifugal machine, of a lining having a cylinder convoluted in cross-section, a conical ring forming the upper portion of the lining, the metal of which the lining is formed being bent outward from the base of the upper portion of 75 each convolution toward said conical ring.

In witness whereof I have hereunto set my hand in presence of two witnesses.

BERNHARD ADOLF OTTO PROLLUS.
